F. A. WARNER

SHIFT LOCK RELEASE FOR TYPEWRITERS

Filed May 26, 1924

UNITED STATES PATENT OFFICE.

FRANK ASHLEY WARNER, OF LOS ANGELES, CALIFORNIA.

SHIFT-LOCK RELEASE FOR TYPEWRITERS.

Application filed May 26, 1924. Serial No. 715,971.

My invention relates to and has for its purpose the provision of a shift lock and release for typewriters embodying a shift key and a shift key lock combined in such manner that only the use of a single key bar is necessary to move and lock the typewriter carriage in shifted position and then release the locking means to allow the carriage to return to normal position.

It is also a purpose of my invention to provide a shift lock and release mechanism which allows the depression of the key bar with either the shift key or the shift key lock, a locking of the key bar in depressed position by the shift key lock and a release of the bar by an actuation of the shift key.

A further purpose of my invention is the provision of a key head for the keys of typewriters which operates to maintain the head against rotation on the key bar and the permanent securing of the legend bearing disk in proper reading position within the key head.

I will describe only one form of shift lock and release mechanism and one form of typewriter key each embodying my invention, and will then point out the novel features thereof in claims.

In the accompanying drawings

Figure 1 is a view showing in side elevation one form of shift lock and release mechanism embodying my invention in normal position and with one key thereof in section;

Figure 2 is a view similar to Figure 1, with the key bar of the mechanism in depressed and locked position;

Figure 3 is a view similar to Figure 2, showing the locking means of the mechanism moved to released position to allow the key bar to return to elevated position;

Figure 4 is a top plan view of the mechanism shown in Figure 3;

Figure 5 is a detail perspective view of the bracket embodied in the mechanism shown in the preceding views;

Figure 6 is a sectional view taken on the line 6—6 of Figure 1;

Figure 7 is a perspective view of the head and shank of the key shown in Figure 1.

Similar reference characters refer to similar parts in each of the several views.

Referring specifically to the drawings, and particularly to Figure 1, my invention in its present embodiment is shown as applied to a key bar B which is of conventional form with the exception that its outer end is not provided with a key. This key bar is pivoted at the point indicated at 15, so that its outer end is capable of being lowered or elevated, and the bar is normally urged to elevated position by means of a spring 16. This key bar is operatively connected (through suitable means not shown) to the carriage of a typewriter so that when its outer end is depressed the carriage will be moved to what is commonly known as shifted position.

The mechanism embodying my invention comprises a bracket which, as illustrated to advantage in Figure 5, comprises a flat bar 17 having fingers 18, a pair of lips 19 on the upper edge of the bar and a lip 20 on the lower edge of the bar, and interposed between the upper lips. All of the lips are adapted to be bent to engage the key bar B and to thus securely hold the bracket in position upon the bar, as clearly shown in Figure 1. The bar 17 is also formed with extensions 21 and 22 in which pins 23 and 24, respectively, are mounted to provide pivots for a pair of key levers 25 and 26, respectively. The lever 26 is provided at one end with what I term a lock key 27, while the lever 25 is formed at one end with a shift key 28. The lock key lever 26 is formed with a slot 29 which receives the pin 24 and a roller 30 mounted on the pin and having rolling contact with the edges of the slot so as to insure proper sliding movement of the lever on the pin. The opposite end of the lever 26 is provided with a release member or lug 31 which is adapted to engage the cam surface 32 of a locking lever 33 pivoted at the point indicated at 34 and normally urged in a clockwise direction by means of a spring 35. The lock lever 33 constitutes part of a means for locking the key bar B in depressed position and this lever is adapted to co-operate with a pin 36 fixed to the shift key lever or bar B and extending through an opening 37 formed in the end of the bar 17.

The shift key lever 25 is pivotally connected to the lock key lever 26 at the point indicated at 38 so that when the key 28 is depressed, a rearward movement of the lever 26 is effected. The key bar B is movable vertically in a slotted plate 39, and secured to this plate is a stop lug 40 which is adapted to be engaged by the pin 36 for limiting the downward movement of the key bar, as will be understood.

In operation, the key bar B normally occupies an elevated position as shown in Figure 1, and in this position of the bar the lock lever 33 has its cam surface 32 in engagement with the pin 36. If it is desired to depress the key bar and lock the bar in depressed position so as to maintain the carriage in shifted position, the lock key 27 is depressed by the finger until the key bar reaches its lowermost position or a position in which the pin 36 engages the stop 40. During downward movement of the key 27 the lever 26 is moved forwardly under the downward pressure exerted on the key so as to elevate the release lug 31 free of the cam 32 and thus prevent such release member from interfering with the movement of the lock lever 33. As the pin 36 moves downwardly, it wipes the cam 32 and because of the curvature of the latter the lock lever 33 is swung until the pin passes off of the cam, when the spring 35 forces the lever 33 forwardly to cause its hooked portion to engage the pin 36 when the bar is locked in depressed position.

To release the key bar so that it can return to elevated position, the shift key 28 is engaged by the finger and depressed, thereby rocking the lever 25 about its pivot 23 to effect a rearward movement of the lever 26. During this movement of the lever 26 the release lug 31 is moved downwardly and rearwardly, engaging the cam 32 and swinging the lever 33 free of the pin 36 so that when the finger is removed from the key 28 the key bar is free to return to elevated position.

From a consideration of Figure 1, it will be clear that the mounting of the lever 25 and its association with the lever 26 are such that the key bar B can be depressed by the key 28 without effecting any movement of the lever 26, and with the lever 26 in normal position it will be clear that during downward movement of the key bar the release lug 31 will engage the cam 32 before the pin 36 passes off of the cam, thus preventing movement of the lock lever 33 to locking position with respect to the pin. The relative positions of the lock lever, release lug and pin as just described are shown in Figure 3.

From the foregoing description it will be manifest that I have provided a shift lock and release mechanism in which the shift key and the lock key are mounted upon a

single key bar, and that the locking of the key bar in depressed position can be effected through an actuation of the lock key 27, a subsequent release of the bar through actuation of the shift key 28, or a depression of the key bar without effecting locking thereof through actuation of the shift key 28.

Referring to Figures 6 and 7, I have here shown a key embodying my invention, which includes a head 41 formed on the upstanding free end of the lever 25, such head being of substantially disk form and split radially at two points and bent to provide right angularly disposed lips 42 and 43 upon which a cover 44 is supported. The cover 44 is of conventional form in that it is formed with lugs 45 bendable to engage the lips 42 and 43 and thus hold the cover upon the head. These lugs 45, by virtue of the construction of the head, are arranged to engage the vertical or unbent portion of the head and to thus limit the rotational movement of the cover 44 of the head. The cover 44 contains a legend bearing disk 46 which is interposed between the usual glass disk 47 and the lips 42 and 43. In order to prevent movement of the disk 46 by the cover, the lips 43 are formed with upwardly bent spurs 48 which embed themselves in the disk and thus lock the latter against movement in the cover.

Although I have herein shown and described only one form of shift lock and release mechanism, and one form of typewriter key, each embodying my invention, it is to be understood that various changes and modifications may be made herein without departing from the spirit of the invention and the spirit and scope of the appended claims.

Having thus described my invention, I claim:

1. In combination, a key bar normally elevated and capable of being depressed to shift a typewriter carriage, means for locking the bar in depressed position, means by which the bar can be depressed without said means locking the bar, and means by which the bar can be depressed to cause said means to lock the bar in depressed position, the second mentioned means being movably connected to the bar and to the third mentioned means in such manner that the locking means is actuated to release the bar by exerting pressure on the second means.

2. In combination, a shift key bar, means for locking the bar in depressed position comprising a pin fixed to the bar, and a lock lever pivoted and normally urged to engage the pin when the bar is in depressed position, a locking key mounted on the bar for pivotal and sliding movements, a release member carried by the locking key, and a shift key pivotally mounted on the bar and operatively connected to the locking key so as to rock and slide the locking key when

the bar is locked in depressed position to cause said release member to engage the locking lever and move the latter free of said pin whereby said bar is allowed to return to elevated position.

3. In combination, a key bar, means for locking the bar in depressed position comprising a pin and a locking lever urged to engage the pin when the bar is in depressed position, a locking key on the bar, a release member carried by the locking key, said key being operable to depress the bar and movable on the bar to move the release member to a position in which the locking lever is allowed to engage said pin for securing the bar in depressed position, and a shift key pivoted on the bar and operatively connected to the locking key for depression of the bar and to simultaneously maintain the release member in a position in which it engages the locking lever to prevent the latter from engaging the pin whereby the bar can be depressed by the shift key without locking the latter in depressed position.

25 4. In combination, a key bar, a bracket having bendable fingers for securing the bracket upon the bar, a locking key including a lever pivoted on the bracket and slotted to allow of limited longitudinal movement thereof, a release lug carried by the lever, means for locking the bar in depressed position comprising a pin fixed to the bar and a pivoted locking lever having a cam urged into engagement with the pin so that when the bar is depressed the pin will co-operate with the cam to move the locking lever into locking engagement with the pin, and a shift key including a lever pivotally connected to the locking key lever in such manner that when depressing the bar by means of the shift key the release lug engages the cam to prevent the locking lever from lockingly engaging the pin and to actuate the locking key lever when the bar is locked in depressed position to cause the release lug to engage said cam and move the locking lever free of said pin whereby the bar can be returned to elevated position.

5. In combination, a key bar, a bracket secured to the bar, a locking key including a lever pivoted on the bracket, and slotted to allow of limited longitudinal movement thereof, a release lug carried by the lever, means for locking the bar in depressed position comprising a pin fixed to the bar and a pivoted locking lever having a cam urged into engagement with the pin so that when the bar is depressed the pin will co-operate with the cam to move the locking lever into locking engagement with the pin, and a shift key including a lever pivotally connected to the locking key lever in such manner that when depressing the bar by means of the shift key the release lug engages the cam to prevent the locking lever from lockingly en-

gaging the pin and to actuate the locking key lever when the bar is locked in depressed position to cause the release lug to engage said cam and move the locking lever free of said pin whereby the bar can be returned to elevated position.

6. In combination, a shift key bar, means for locking the bar in depressed position comprising a pin fixed to the bar, and a lock lever pivoted and normally urged to engage the pin when the bar is in depressed position, a locking key mounted for movement on the bar, a release member carried by the locking key, and a shift key mounted for movement on the bar and pivotally connected to the locking key, so as to move the latter when the bar is locked in depressed position to cause said release member to engage the locking lever and move the latter free of said pin whereby the bar is allowed to return to elevated position.

7. A device of the character described comprising a bracket adapted to be secured to a shift key bar, a locking key mounted for movement on the bracket and having a release member, and a shift key operatively connected to the locking key and movably mounted on the bracket in the manner and for the purpose described.

8. A device of the character described comprising a bracket adapted to be secured to a shift key bar, a locking key mounted for pivotal and sliding movements on the bracket and having a release member adapted to occupy two extreme positions and a shift key pivotally connected to said locking key, whereby said release member is movable to one extreme position when the locking key is depressed and to the other extreme position when the shift key is depressed.

9. A device of the character described as embodied in claim 8 wherein the locking key has a pin and slot connection with said bracket.

10. A device of the character described as embodied in claim 8 wherein said bracket is provided with bendable lugs for clamping the bracket to the bar, and an opening adapted to receive a pin secured to the bar for positioning the bracket longitudinally of the bar.

11. In combination, a key bar normally elevated and capable of being depressed to shift a typewriter carriage, means for locking the bar in depressed position, means mounted for movement on the bar by which the latter can be depressed to cause the first means to lock the bar in depressed position, and means mounted for movement on the bar and operatively connected to the second means by which the bar can be depressed without the first means locking the bar.

12. In combination, a key lever, a head of substantially disk form on the lever, said

head being split inwardly from its edge at two points and bent to provide a pair of spaced lips projecting from one side of the head and a single lip between said lips projecting from the opposite side of the head, said pair of lips having their free ends pointed and upturned to provide prongs, a

cover for the head having a legend bearing disk therein, and means for securing the cover to the head to effect penetrating engagement of the prongs with the disk, to thereby prevent rotation of the latter upon the head.

FRANK ASHLEY WARNER.
